UNITED STATES PATENT OFFICE.

WALTER E. CLAUSSEN, OF HARTFORD, CONNECTICUT.

RECEPTACLE.

1,296,923.

Specification of Letters Patent. Patented Mar. 11, 1919.

Application filed March 18, 1915. Serial No. 15,351.

To all whom it may concern:

Be it known that I, WALTER E. CLAUSSEN, a citizen of the United States, residing at Hartford, in the county of Hartford and 5 State of Connecticut, have invented certain new and useful Improvements in Receptacles, of which the following is a specification.

This invention relates to bottles, the object of the invention being to provide an article of this character which can be easily and inexpensively made and which can be advantageously utilized for receiving and carrying substances of radically-different 15 kinds, either in a liquid, solid or semi-liquid state.

In the drawings accompanying and forming part of the present specification I have shown in detail several of the many different forms of embodiment of the invention. 20 These will be set forth fully in the following description to enable those skilled in the art to practice the invention. As will be understood I do not restrict myself to such disclosure; I may depart therefrom in material respects within the scope of the invention defined by the claims following said description.

Referring to said drawings: 30 Figure 1 is an elevation partly in section of a partly formed bottle involving the invention.

Fig. 2 is an elevation of the bottle at a further stage in its manufacture, the bottom 35 closure constituting another part of the bottle being omitted from this and the preceding view.

Fig. 3 is a view of the bottle with the bottom closure set therein but not secured in 40 place, the upper part of the illustration being in section and the remainder in elevation.

Fig. 4 is an elevation of the finished bottle or complete article.

Fig. 5 is a cross section of the bottom 45 closure associated with the bottle of Fig. 4.

Figs. 6 and 7 are corresponding views of modified forms of bottom closure, and

Fig. 8 is a top plan view of the closure of 50 Fig. 5.

Figs. 9 to 17 inclusive are sectional views hereinafter more particularly described.

Like characters refer to like parts throughout the several figures.

55 Referring first to Figs. 1 to 4 inclusive. The bottle there shown comprises a body as

2 and a bottom as 3 both of pulp. The body 2 can be inexpensively made and possesses considerable strength. As shown it is composed of a plurality of layers, for example 60 three, the outer layer being designated by 4, the inner layer by 5 and the intermediate layer by 6. The inner and outer layers are of a finer grade of stock than the intermediate layer. The inner and outer layers are 65

comparatively thin as compared with the intermediate layer 6. The outer and inner layers when both are present, may be coated with a waterproofing, fireproofing or other substance, or they and the intermediate 70 layer may be so prepared or they may be conditioned to resist the action of chemicals or to conform to the particular employment of the receptacle, these being merely 75 details. I prefer that the body 2 both internally and externally be smooth, and this condition can be secured during the process of manufacturing the same.

While the body 2 is of integral construction, I do not limit myself in this regard, as already observed, 80 for as intimated, the invention involves a sectional receptacle and wherein the sections are held together by the compression of the pulp. In the construction now being described, which is the preferred one, the body 85

is in one piece and the bottom 3 is held in proper operative relation with the body by the compression of the pulp on the body, this compression being preferably secured while the pulp composing the body, is in a 90 damp or moist condition and also preferably by heating the body. I might state that after the compression of the pulp body upon the bottom, the body when dried obtains a still further and substantial hold 95 upon the bottom. The strength of the receptacle is obtained by the intermediate low grade or quality layer 6, the finish being obtained by the inner and outer layers of a better quality of pulp. In this way a receptacle can be produced having all the appearance and all the advantages of one made

from high grade pulp but which can be produced cheaper than the latter without the sacrifice of strength. As a matter of fact 100 105 a receptacle constructed in accordance with the invention is stronger than one made of high grade pulp which in order to be marketed at a profit must be made comparatively thin. The body 2 can be made after 110

the fashion followed in making those of the ordinary kind of pulp. After a layer 5 is

formed the layer 6 may be deposited upon it, subsequent to which the finishing layer 4 will be interposed upon the coarse pulp layer 6.

- 5 The receptacle may as shown have a reduced neck 7 which may have an internal seat 8 to receive a paper cap. When so formed the receptacle will be utilized for containing milk or some other liquid. The 10 bottle, of course, may be used for entirely different purposes and a cap other than that referred to may be provided. After the bottle has been initially formed or while its body is in the condition shown in Fig. 15, said body is compressed throughout its extent except at and around the base, this part being left enlarged as at 9, the enlarged part presenting stock sufficient to be compressed into or upon the bottom closure 20 3 which as shown has a circumferential annular groove or channel 10 into which the damp or moistened stock 9 at the bottom of the body 2 can be compressed by the aid of dies or otherwise, the receptacle when the 25 stock is pressed into the groove 10 being smoothed down so as to obtain the ultimate article shown in Fig. 4.

In Fig. 6 I have shown a closure 11 having two peripheral circular grooves 12, one 30 of rectangular form in cross section and the other of rounded form in cross section, the thickened pulp being pressed into these grooves to obtain a double interlock between the body and the bottom of the receptacle, 35 each interlock being in the form of a tongue and groove joint. In Fig. 7 the bottom 13 has a circumferential circular bead 14 to be pressed into the pulp of the body as 2. That is to say the pulp of the body will be 40 reduced cross sectionally to nearly its entire extent leaving a circular portion at the bottom in its initial condition and into this bottom and relatively thick portion of the pulp the bead or tongue 14 will be forced.

45 In Fig. 9 the body of the receptacle is denoted by 15 and it is made like the body described in connection with Fig. 1, there being a thickened portion 16 left at the base thereof which is compressed into the annular undercut groove 17 of the bottom 18 fitted in the open lower end of said body 15, the flange 19 of said bottom 18 overlying the bottom edge of said body 15. When the two parts are assembled the exterior of the body 50 will be smoothed down. In Fig. 9 I have shown the thickened part 16 in its original condition on the left and on the right

pressed into the said groove 17. In Fig. 10 the body 20 receives the dished bottom 21. The base of the body is left thickened as before, the thickened portion being brought over the outer face of the bottom 21 and pressed and smoothed down upon the same. In Fig. 11 I have shown a bottom 22 of pulp, the marginal portion being left thick or of greater cross sectional extent as at 23 than the remainder thereof. This bottom is forced into the body 24 of Fig. 12, the act of which causes the thickened portion 23 to be forced within the bottom 22 as shown at the left 70 in said figure. When the bottom 22 is properly into the body 24, this thickened portion is forced into the groove 25, the annular tongue or bead 26 of the thickened part of the pulp being projected into said 75 groove as shown on the right in said Fig. 12.

In Fig. 13 is shown a bottom 27 of pulp thickened as at 28. This cap 27 is adapted to fit the body 29 as shown in Fig. 14, the bottom edge of the body 29 being thickened as at 30 and the two thickened portions 28 and 30 being compressed together and smoothed down. In Fig. 15 I have shown a bottom 31 to fit the body 32 of Fig. 16, the body 32 being thickened as at 33. This 85 cap 31 has a circular circumferential groove 34. The body 32 and bottom 31 are shown assembled in Fig. 17, the thickened portion 33 of the stock of the body 32 of Fig. 16 being forced into the groove 34 to interlock said body 32 and bottom 31. As already noted, it is not essential that the body of the receptacle be of one piece.

What I claim is:

1. A bottle comprising a body and a bottom both of pulp, initially distinct from each other, the bottom being secured to the bottom of the body by the compression together of the marginal portions of the two parts while said two parts are in a 100 plastic condition and while the compressed-together portions thereof are of greater thickness than the adjacent portions thereof.

2. A bottle comprising a body and a bottom both of pulp, the two parts being cohesively united by compression while the pulp is in a plastic condition.

In testimony whereof I affix my signature in presence of two witnesses.

WALTER E. CLAUSSEN.
